LIP STICK CONTAINER

Ellison S. Irelan, Elgin, Ill., assignor to Illinois
Watch Case Company, Elgin, Ill., a corpora-
tion of Illinois

Application February 21, 1934, Serial No. 712,371

9 Claims. (Cl. 206—56)

This invention relates to a container for lipsticks and like articles. The present improvements have to do with the provision of a reflecting surface, such as a mirror, on one of the walls 5 of the container within which the lipstick or other article is enclosed; and also with the provision of an actuating slide by which the lipstick or other article may be advanced and maintained in various positions of advance within a holder 10 that is accommodated within the container.

It is accordingly an object of my invention to incorporate a mirror in the construction of the present lipstick container, and to do this in a manner which is protective to the mirror, which 15 involves but a minimum of expense in its production and a minimum of space for its accommodation, and which affords at the same time a better grip for the fingers when seizing the container during the act of withdrawing the lipstick or other article therefrom. It is further 20 an object to provide for the lipstick an actuating slide together with means by which it is locked in various positions of adjustment and with other means for releasing the slide automatically when 25 the lipstick holder is advanced within the container with which it is associated. These and other objects are accomplished by my invention of which a suggestive embodiment is shown in the accompanying drawing in the manner following:

Figure 1 is a perspective view of a container for a lipstick or the like;

Fig. 2 is a transverse section through the container and enclosed lipstick, taken on line 2 of 35 Fig. 1;

Fig. 3 is a central longitudinal section on line 3 of Fig. 2;

Fig. 4 which is a view similar to Fig. 3 shows the lipstick partially withdrawn from the container;

Fig. 5 is a view similar to Fig. 4 showing the slide in an advanced position as when the lipstick and holder is being slid within the container whose mirror in this instance is of modified construction;

Fig. 6 is a bottom plan view of the lipstick holder showing the slide and locking means therefor;

Fig. 7 is a transverse section taken on line 7 50 of Fig. 6; and

Fig. 8 is a detail in perspective of the spring associated with the slide.

The present construction is adapted for enclosing and protecting an article A such as the lipstick shown which may be adjustably supported

in a holder H slidably fitted within a container C in the form of an elongated open-ended case having two opposite walls which are relatively wide. The holder may be of conventional form in that it comprises a square tube open at one 60 end for slidily receiving a cap D affixed to one end of the lipstick or other article. Fitted within the cap and bearing against the end of the lipstick is a plate 10 spaced from the end of the cap to provide a narrow chamber wherein may 65 be accommodated a leaf spring E having one end portion 11 vertically disposed and then bent around to provide a horizontal portion 12 which extends adjacent the upper wall of the cap and finally executing a return bend 13 to provide 70 a return portion 14 which carries a neck 15 on which is a head 16 forming an actuating slide. Extending laterally from the neck is a shoulder 17, and upon the forward face of the head is a cam nose 18. The neck passes through a slot 19 75 extending for substantially the length of the lower wall of the tube and also in the corresponding wall of the cap. The slide may be used as an operating medium for adjusting the lipstick lengthwise of the tube to a desired position of exposure. 80 Affixed to the cap at the end of the tube is a plate 20 having its opposite edges extended slightly beyond the cap.

The slot edge proximate to the shoulder 17 is racked as by serrations or teeth 21, permitting 85 the shoulder to engage therewith. The tension of the spring acts to push out the slide so that the shoulder is normally engaged with the rack, thereby locking the slide, and with it the lipstick, against longitudinal movement within the tube 90 holder. It is only when the slide is depressed that the shoulder becomes disengaged so that adjustment of the lipstick to another position may be made.

The lipstick together with its holder is adapted 95 to be received within the container case through the open end thereof. A slot 22 is extended from this open end for a slight distance so as to receive the neck of the slide.

When the slide is advanced within the case, the 100 cam nose on the slide is brought into engagement with the end of the slot 22 (see Fig. 5), thereby depressing the slide with the result that the shoulder is thereupon disengaged from the rack; continued inward movement of the holder, which 105 would otherwise be prevented, is accordingly made possible by this release which takes place automatically. The holder fits snugly, yet slidily, against two of the narrower opposite case walls. An appreciable space is left between the holder 110

and the case top as viewed in the several figures of the drawing. So that the holder may remain positioned snugly yet slidingly against the bottom 23 of the case, a pair of bars 24 may be affixed 5 to side walls of the case in overlying relation to the holder. These bars accordingly serve in conjunction with the bottom of the case as guides in the sliding movements of the holder.

The case top which is one of the wider walls 10 is apertured so as to leave but a narrow frame 25 extending around the margins thereof. Received between this frame and the bars 24 is a plate 26 having a polished or mirrored surface. This plate occupies a sunken position with reference to the 15 top of the case and, in cooperation with the frame, provides a top wall for the container.

When the holder is positioned within the case, as shown in Fig. 3, the plate 20 may abut the open end of the case, so as to serve as a closure therefor. The edges of this wall protrude somewhat 20 beyond the top and bottom of the case as at 30 and 31 so as to provide a hold for the fingers when the lipstick is to be removed from the case. In this operation, the mirrored surface of the case 25 is protected from contact by the fingers due to the raised frame in surrounding relation thereto. In consequence, the fingers will ordinarily rest upon this frame or upon one side thereof when holding the case preparatory to removal of the 30 lipstick therefrom.

It is possible, of course, that the mirror thus incorporated into the case may be constructed otherwise than as described. For example, as suggested in Fig. 5, the central portion of the top 35 wall 35 of the case may be sunken in relation to the surrounding edges 36. In such a construction the surface of the sunken panel is polished or mirrored to provide the reflecting surface. In use, the fingers take hold of such a case without 40 contacting the mirror, the same as has already been described.

I claim:

1. An article container comprising an elongated case open at one end, an article holder slidible 45 into and out of the case through its open end, a cap slidably fitted within the holder in fast connection with an article therein, an actuating slide in connection with the cap, and means with which the slide is in resilient engagement for securing 50 the cap and article in various positions of adjustment longitudinally of the holder, said actuating slide having means cooperating with the open end of said case for retracting the cap within the holder.

55 2. An article container comprising an elongated case open at one end, an article holder slidible into and out of the case through its open end and provided with a longitudinal slot having a rack therein, an actuating slide in resilient connection 60 with an article which is slidably fitted within the holder, and means on the slide adapted normally to engage with the rack for securing the article in a fixed position of adjustment longitudinally of the holder, said slide having means cooperating 65 with the open end of said case to release the same for retracting the slide within the holder.

70 3. An article container comprising an elongated case open at one end, an article holder slidible into and out of the case through its open end and provided with a longitudinal slot having an associated rack, an actuating slide, a resilient connection extending from the slide through the slot to an article which is slidingly fitted within 75 the holder, means on the slide normally engaged

with the rack for securing the article in a fixed position of adjustment longitudinally of the holder, and cam means on the slide adapted to engage with the case when the holder is advanced therein for releasing the slide from engagement with the rack whereby the article within the holder is free to move lengthwise therewithin. 80

4. An article container comprising an elongated case open at one end, an article holder slidible into and out of the case through its open end, 85 means within the holder in fast but resilient connection with an article slidable therein, there being in the holder a longitudinal slot having an associated rack, an actuating slide movable lengthwise of the slot and extending therein to join the resilient connection therewithin, and means on the slide normally engaging with the rack, whereby to lock the article in a selected position of adjustment relative to the holder, said slide having means cooperating with an end portion of said case to release the same for retracting the slide within the holder. 90

5. An article container comprising an elongated case open at one end having its walls in the form of rectangular plane surfaces two of which are 100 relatively wide of which one is centrally apertured to define a frame one side of which serves as a finger hold, a panel mounted within the aperture in sunken relation to the frame, an article holder slidible into and out of the case through 105 its open end provided with protruding means adjacent the finger hold adapted to serve as a complementary finger hold when the article holder is pulled to accomplish its endwise removal from the case, and means within the case supporting 110 the panel in place adjacent the frame and engageable with the article holder at remote points to guide the latter in its sliding movements relative to the case. 115

6. A lipstick container comprising an elongated case open at one end having its walls in the form of rectangular plane surfaces two of which are relatively wide of which one is provided with a sunken panel surrounded by a raised margin adapted normally to protect the sunken panel 120 from contact by the fingers when the case is manually held, and a lipstick holder slidible into and out of the case through its open end provided with means protruding beyond the raised margin of the panel and adjacent thereto to serve 125 as a finger hold when the holder is pulled to accomplish its endwise removal from the case.

7. An article container comprising an elongated case open at one end, an article holder slidible into and out of the case through its open end, an actuating slide in connection with an article which is slidably fitted within the holder, coacting means on the slide and holder for securing the article in a fixed position of adjustment longitudinally of the holder, and other means on the slide adapted to engage with the case when the holder is advanced therein for releasing the slide whereby the article within the holder is free to move lengthwise therein. 130

8. An article container comprising an elongated case open at one end and having a slot extending lengthwise inwardly from its open end for a short distance, an article holder slidible into and out of the case through its open end and provided with an elongated slot extending lengthwise thereof in line with the short slot of the case, means slidably fitted within the holder in fast connection with one end of an article therein, an actuating slide in connection with said means and extending through the holder slot to lie in 140 145

part exteriorly thereof and within the case slot through the open end of which it is free to enter or leave, the closed inner end of the case slot forming an abutment for the actuating slide such that it is moved lengthwise of the holder to a position adjacent one end thereof whenever the holder is slid clear into the case.

9. An article container comprising an elongated case open at one end and having a slot extending lengthwise inwardly from its open end for a short distance, an article holder slidable into and out of the case through its open end, and provided with an elongated slot extending lengthwise thereof in line with the short slot of the case, an actuating slide extending through the holder slot to lie in part exteriorly thereof and within the case slot through the open end of which it is free to enter, positive locking means with which the slide is in resilient engagement for securing the slide in a fixed position of adjustment longitudinally of the holder, and means connecting the slide with an article that is movably fitted within the holder, said slide having means cooperating with the slotted end of the case to release the same from said locking means.
